CLAIM

The ornamental design for a dish holder, as shown and described.

DESCRIPTION

FIG. 1 is a front view of the dish holder;

FIG. 2 is a rear view of the dish holder;

FIG. 3 is a left side view of the dish holder;

FIG. 4 is a right side view of the dish holder;

FIG. 5 is a top view of the dish holder; and,

FIG. 6 is a bottom view of the dish holder.

The broken-line disclosure in the views is for illustrative purposes only and forms no part of the claimed design.
